FLUSH VALVE

Bert O. Tilden, Trenton, N. J., assignor to
 B. O. T. Manufacturing Company, Trenton,
 N. J., a corporation of New Jersey

Application February 1, 1933. Serial No. 654,678

5 Claims. (Cl. 4-58)

This invention relates to improvements in water closet flush valves, designed especially for water conservation, quiet flushing action, and greater economy of construction, both as to materials and production cost.

The invention relates particularly to improvements in the flush valve shown and described in my United States Patent No. 1,861,250, dated May 31, 1932.

10 The primary object of the invention is to generally improve the design as well as the mechanical arrangement of the valve-supporting and operating parts of my former patent, to render said parts more simple and positive in 15 construction and operation and adapted to be molded preferably from rubber or other relatively light material that quickly hardens and may be assembled direct from the molds without requiring any machining, thereby greatly 20 reducing the time, labor and cost of producing said mechanisms. A further object is to quicken the flushing of the bowl, as well as eliminate the usual annoying flushing noises, by the expulsion of entrapped air from the vicinity of 25 the rim of the bowl, whereby the full volume of the flushing water may freely gravitate towards the bowl and initiate the flushing, without causing preliminary waste of water in order to overcome the back pressure, by forcing the confined 30 air with attendant noise through the numerous small vents or outlets of the rim, as heretofore. And a further object is to provide a novel composite valve that may be removably mounted upon the lower end of the tubular stem and 35 comprising a stiff and rugged disc which is shod with a plane compressible part that engages the valve seat.

I attain these objects by the means set forth in the detailed description which follows, and 40 as illustrated by the accompanying drawing, in which—

Figure 1 is a central vertical section taken on line 1—1 of Fig. 2. Fig. 2 is a top plan view of the device of Fig. 1. Fig. 3 is a top plan 45 view of the annular float with the tubular stem removed. Fig. 4 is an elevational view of a tubular stem. Fig. 5 is a horizontal section on line 5—5 of Fig. 1. Fig. 6 is a broken central vertical section corresponding to portions of Fig. 50 1, showing the valve partially opened; the arrows in this view showing the path taken by the entrapped air displaced by the first slight opening of the valve. Fig. 7 is a horizontal section taken on line 7—7 of Fig. 4. And Fig. 8 is an elevational view taken in the direction of the arrow 55

in Fig. 7, showing the method of applying the lift-rod to the valve stem.

In the instant case, I have adopted generally the principle of my former annular valve and gravitational tubular valve stem, which are rendered buoyant during each flushing interval by an integral float that is enclosed by and reciprocates in a cup-shaped chamber, the said float being immersed whenever the chamber is submerged by the flooding thereof with the flushing water, and the stem passing axially and loosely through an opening in the bottom of the chamber which serves to guide the stem as well as to effect the substantial draining of said chamber concurrently with the complete emptying of the flush tank.

It has been discovered since the granting of my former patent that to utilize the axial opening in the bottom of the float chamber for effecting the major discharging of the contents of said chamber renders it necessary to so enlarge the area of said opening beyond the diameter of the stem as to virtually destroy the function of the stem-guiding means. In practice, it has been found that the said axial opening should be limited to about one thirty-second of an inch clearance around the tubular stem, as shown in the drawing, and that to increase the said clearance to the extent necessary to properly time the closing of the valve would greatly exceed the normal clearance required for the proper and sure seating of the valve, since the said enlarged opening would allow the stem to shift or wobble due to the continuing action of the strong flushing stream and therefore tend to dangerously cant the valve.

To this end, the major drainage work in the present case has been preferably assigned to an auxiliary vent or opening, which, according to my former patent, performs the dual function of preventing a vacuum in the lower portion of the float chamber and of effecting the complete drainage of the portion of said chamber, that lies below the plane of the annular water-friction producing ledge, to prevent accumulation of sediment and otherwise fouling of said chamber. The imposing of this additional function upon the auxiliary vent in the instant case renders it necessary to greatly increase its area in order that it may effect substantially the whole of the draining of the float chamber and the closing of the valve concurrently with the complete emptying of the flush tank, which in point of time is ordinarily effected in about ten seconds.

As a result of this improved construction and arrangement, and in virtue of the surface tension

of the water in the float chamber, the downward or closing movement of the valve and related parts is continuous and steady, due to the accurately calculated rate of the major discharge through 5 the auxiliary opening which may be supplemented to a slight extent by the lighter discharge via the restricted clearance around the tubular stem.

By making the float chamber, float and overflow-valve-stem of molded rubber instead of 10 metal, the said parts are more easily and definitely controlled; the relative lightness of the valve-control parts renders them more buoyant and contributes in great measure to their steady descent from the start of the flushing to the closing 15 of the valve, which is greatly desired.

In the drawing, 2 represents the bottom of a China or other flush tank, which is formed with the usual central opening 2' for the discharge of the flushing water. 3 represents a cage-like 20 metal valve body which is disposed concentric to the opening 2', the body being formed with the usual threaded spud portion, as 3', which extends through said opening, and may connect with a water closet bowl (not shown). The body 3 25 is also formed with an upwardly facing annular valve seat 3a, which is preferably disposed slightly below the plane of the inner face of the bottom 2 to enable the tank to be completely emptied at the end of each flushing operation. The cage- 30 portion of the body 3 extends above the seat 3a and includes a ring-like portion 3b that is supported by angular legs 3c, and is formed with perforated lugs 3d that carry set-screws 4b. The legs 3c are so spaced as to insure the free admission 35 of the water to the outlet defined by the seat 3a. At the base of the cage, the spud 3' is formed with an annular flange 3e, which seats upon a sunken annular ledge 2d that surrounds the opening 2', the joint between the flange 3e 40 and the ledge being sealed by a packing 3f. The annular opening below the ledge 2d is preferably sealed by a beveled rubber packing ring a, which is clamped tightly against the bottom 2 by a nut a'.

4 represents a cylindrical float chamber normally open at its top 4' and having an integral bottom 4a which rests upon the ring 3b and loosely engages the lugs 3d; said chamber being held rigidly in place by the thumb-screws 4b, as shown in Figs. 1 and 2. The bottom 4a is formed with an axial opening 4c which is surrounded by an integral up-standing annular flange 4d that coincides with the valve seat 3a, and also with an auxiliary vent x, which drains the chamber at the end of each flushing interval.

The flush valve preferably consists of a plane annular plate 6 which is threaded to receive the lower reduced and threaded end 5' of the tubular stem 5 that is preferably disposed in axial alignment with the seat 3a. In practice, the plane bottom face of the plate 6 is shod with a washer-like sheet of leather or other slightly compressible material, as 6', that engages the seat 3a and is preferably of the same diameter as the plate and free to expand and contract, and this leather part is preferably held in place by a nut 6a, shown in Figs. 1 and 6. From the valve 6, the tube 5 extends upwardly through opening 4c and float chamber 4 and terminates at a point an inch or more above the normal level of the flushing water, whatever that may be.

The tube 5 in the present case performs the usual function of the well-known overflow pipes which ordinarily have been disposed in various parts of the flush tanks and as a rule have no di-

rect connection with the flush valves, although according to some practices, these pipes have been supported rigidly by the valve bodies. In the instant case, the valve is detachably secured to the end 5' of tube 5, so that the tube also serves as the valve stem and may be raised and lowered for opening and closing the valve, without interfering with its important function of carrying off the surplus water in case the ball-cock fails to close for any reason. For this purpose, the bore of the overflow 5 is preferably straight and unrestricted, carries the excess water through the valve 6, and discharges the same directly into the spud 3', without disturbing the valve. The tube 5 preferably passes loosely through the opening 4c, the sole guide for the tube, and within the chamber 4 the tube is fitted with an air-tight drum 7 that serves as the float by which the tube 5 and valve 6 may be suspended during the flushing operations. The drum 7 is preferably annular in order to provide a clear axial opening or well 7', to loosely receive the tube 5, instead of the tube passing through the air chamber, as heretofore. To this end the tube 5 is formed medially with an annular molded 100 shoulder 5a and immediately below said shoulder with external threads 5b that engage complementary threads 7a that are molded in the upper end of the well 7', as shown in Fig. 1; the well 7' below threads 7a preferably being of larger 105 diameter than tube 5 to prevent cramping of the parts when they are assembled.

It is important that the valve 6 and the shoulders 5a-5c of stem 5 be parallel to the plane top and bottom ends of the float in order that all of 110 said parts may be disposed truly axially and therefore perfectly balanced to insure the positive seating of the valve by the draining of the float chamber. The portion of the tube 5 below the shoulder 5a is preferably enlarged, as at 5d in 115 Figs. 1 and 4, to facilitate molding the threads of the reduced lower end 5' of the tube, so as to provide the shoulder 5c without contracting or choking the bore of the tube in the vicinity of said shoulder.

The float 7 is preferably of less diameter and height than the chamber 4, to enable the flushing water when its level rises above the top of the chamber to gravitate past the float and fill all empty spaces in the chamber. This filling of the 125 empty spaces effects the complete enveloping of the float 7 during and after each refilling of the tank, which continues until tube 5, float 7 and valve 6 are lifted to initiate the next flushing operation. This sudden opening of the valve increases the depth of the water below the float to such extent that the float and stem will be held suspended until this excess water drains off through the vent x, as explained.

The surface tension or friction of the water, 135 especially that portion that fills the relatively narrow space 4x between the float 7 and the inner wall of the chamber 4, as well as the thinner film that fills the clear space between the pipe 5 and the adjacent surface of the opening 4c which is 140 more or less influenced by capillary attraction, plays an important part in the timing of the descent of the valve, since these forces in virtue of which they exert a pull that tends to resist and retard as well as cushion the gravitation of the 145 float and tube 5, and must be taken into account when the area of vent x that determines the rate of discharge through the openings 4c and x is computed. The importance of this retarding of the closing movement of the valve will be appre- 150

- ciated when it is understood that in this type of water closet the siphon action is timed to terminate while the flush tank still contains sufficient water to properly refill the trap of the bowl, and 5 the completion of this refilling should coincide with the emptying of the float chamber 4 and the consequent closing of the valve 6, which immediately follows the complete emptying of the tank.
- 10 The valve 6 may be opened by any of the well-known manually rockable means that may connect with a vertical reciprocating lift-rod, as 9, which for this purpose is formed with a loop 9'; the rod being slidable in a perforated lug 9a, 15 which may be integral with the tube 5 and is preferably formed with an oblique slot 9b that intersects the perforation, and enables a reduced portion, as 9c, to enter the slot when assembling the parts, as shown in Fig. 8. By this construction, the rod when later disposed erect and connected with the operating means (see Fig. 1), is not liable to escape from the lug. The lower end of rod 9 is preferably upset, as at 9d, to provide an integral head that engages the lug and 20 lifts the valve stem.
- It has long been the complaint of the present-day type of flushing rims that the air normally present in the cavity of the rims becomes entrapped by the initial flow of the flushing stream 25 and must be expelled from the rim in order that the full volume of the water may be delivered to the bowl to effect the proper siphon action. To overcome the back-pressure created by this entrapped air, the latter has to be forced through 30 the small orifices that comprise the sole exits for the water from the rim. This not only requires an additional amount of water and retards the siphon action, but also creates annoying noises common to most of the modern water closets.
- 35 It is an object of the present invention to quicken the flushing of the bowl and eliminate waste of water as well as the usual flushing noises, by expelling the entrapped air from the vicinity of the rim of the bowl at the start of the flushing operation. To accomplish this, the lower end 5' of the tube 5 has been extended a considerable 40 distance into the spud 3' primarily for the purpose of preventing the first of the flushing water from forming a film horizontally across the valve seat and sealing the lower end of tube 5, thereby 45 preventing the free escape of the entrapped air via the said tube, as indicated by the arrows in Fig. 6. In order to accomplish the last-named object, 50 advantage has been taken of the substitution of the overflow pipe 5, extending through the valve 55 seat, for the solid stems in common use. The operation whereby the flushing of a closet bowl is rendered quicker and less noisy is as follows: When the valve 6 is initially raised to start the 60 flushing, and as long as the end 5' of pipe 5 remains below the plane of seat 3a, the flushing water tends to flow down the inner surface of the spud 3'. This momentarily establishes a clear flue-like passage in the line of the axis of the spud 65 that communicates with the bore of the pipe 5. When the water reaches the usual shallow distributing chamber which according to my former patent lies directly beneath the discharge opening 2' of the tank bottom and communicates with the rim cavity, the water instantly displaces the 70 air confined between the rim of the bowl and the valve seat 3a, and the air then takes the course of least resistance by ascending through the said flue and escapes via the bore of the overflow pipe 75 5, as indicated by the arrows in Fig. 6. This in-
- stantly relieves the rim of the back pressure, and allows the water to flow freely and quietly through the exits of the rim and accelerate the copious flushing of the bowl, by the time the end 5' of the pipe 5 rises to the plane of the seat 3a.
- Having thus described my invention, what I claim, is—
1. A water closet flush tank having a flushing opening in its bottom, a seat concentric to said opening, an annular valve to close said opening, a tubular stem to support the valve having a shoulder which defines a reduced portion that passes through the valve and disposes the valve at right angles to the axis of the stem, said stem having a molded medial shoulder and threads adjacent said shoulder, an annular float having concentric threads to engage the medial threads of the stem, an open top chamber to loosely enclose the float, the bottom of the chamber having an axial opening to receive and guide the stem, said chamber adapted to be flooded with the flushing water to envelop and render the float buoyant, the bottom of said chamber being formed with a relatively large eccentric opening adapted to drain said chamber to effect the closing of the valve at a predetermined moment, and means to raise the stem and float to start the flushing operations. 80
2. A water closet flush tank having a discharge provided with a valve seat, a tubular stem having a shoulder between its ends and having an enlarged threaded portion beneath the shoulder, a drum-like float having a central circular wall connected at its ends to the top and bottom walls of the float to render the float air-tight and to provide a well receiving the stem and having an internal diameter larger than the external diameter of the stem, the top of the float engaging the shoulder of the stem whereby to close the upper end of the well, and having internal threads engaged with the threads of the stem, and the bottom of the well being open, the lower end of the stem being reduced to form a shoulder and being threaded, a valve for the discharge engaged with said last named shoulder, and a nut on said threaded lower end of the stem to rigidly hold the valve against the last named shoulder. 85
3. A water closet flush tank having a discharge provided with a valve seat, a tubular stem having a shoulder between its ends and having an enlarged threaded portion beneath the shoulder, a drum-like float having a central circular wall connected at its ends to the top and bottom walls of the float to render the float air-tight and to provide a well receiving the stem and having an internal diameter larger than the external diameter of the stem, the top of the float engaging the shoulder of the stem whereby to close the upper end of the well, and having internal threads engaged with the threads of the stem, and the bottom of the well being open, and a valve for the discharge carried by the lower end of the stem. 90
4. A water closet flush tank having a discharge, a spud in the discharge having a valve seat, a tubular stem having a reduced lower end forming a shoulder and being threaded, a valve for the discharge mounted on the stem and abutting the shoulder, a nut engaged with the threads of the stem and abutting the valve to rigidly hold the latter against the shoulder, said reduced lower end of the stem projecting into the spud for such distance so as to initially deflect the flushing water from the bore of the 95

stem upon upward movement of the valve from its seat, and a float on the stem.

5. A water closet flush tank having a discharge provided with a valve seat, a tubular stem, a drum-like float having a central circular wall connected at its ends to the top and bottom of the float to render the latter air-tight and to provide

a well receiving the stem, the internal diameter of the well being greater than the external diameter of the stem, means to mount the float on the stem, and a valve for the discharge carried by the stem.
